Des. 237,546
Patented Nov. 4, 1975

237,546

WALL FOUNTAIN

Patrick T. Kelly, Los Angeles, Calif., assignor to Haws
Drinking Faucet Company, Berkeley, Calif.

Filed May 10, 1973, Ser. No. 358,968

Term of patent 14 years

Int. Cl. D23—01

U.S. Cl. D67—4

FIG. 1.

FIG. 6.

FIG. 2.

FIG. 3.

FIG. 4.

FIG. 5.

FIG. 7.

FIG. 1 is a perspective of a fountain with a drinking fixture inserted therein in broken lines for illustrative purposes only;

FIGS. 2, 3, 4 and 5 are respectively the front, left side, right side and back views of the fountain shown in FIG. 1; and

FIGS. 6 and 7 are respectively the top and bottom views of the fountain shown in FIG. 1.

I claim:

The ornamental design for a wall fountain, substantially as shown and described.
